CLOSURE FASTENER FOR CONTAINERS

Edward P. Linch, Philadelphia, Pa.

Application January 19, 1938, Serial No. 185,663

6 Claims. (Cl. 215—94)

This invention relates to closure fasteners for containers and more particularly to an improved construction and conformation of wire loop for fastening closures in place on containers.

5 It is an object of the present invention to provide an improved one piece wire structure for fastening container closures in place.

It is a further object of the present invention to provide a closure fastener for containers which 10 will have a higher sealing efficiency than has heretofore been obtained.

It is a further object of the present invention to provide an improved form of closure fastener particularly adapted for use on carboys where 15 strength and reliability are essential.

It is a further object of the present invention to provide an improved form of wire loop for use in fastening container closures in position.

It is a further object of the present invention 20 to provide an improved form of wire loop for use in fastening container closures which is provided with a portion for indicating the correct positioning of the wire loop on the container.

Other objects of the invention will appear from 25 the annexed specification and claims.

The nature and characteristic features of the invention will be more readily understood from the following description, taken in connection with the accompanying drawing forming part 30 hereof, in which:

Figure 1 is an elevational view of a portion of a container showing a device made in accordance with the present invention and in place on the container for fastening the container closure;

35 Fig. 2 is a fragmentary side elevational view of the arrangement shown in Fig. 1, as seen from the left thereof;

Fig. 3 is a horizontal sectional view taken on the line 3—3 of Fig. 1 and looking up from 40 beneath;

Fig. 4 is a plan view of a preferred form of wire loop before being placed on the container; and

45 Fig. 5 is a fragmentary side elevational view of a portion of the wire loop as bent before being placed on the container.

It will, of course, be understood that the description and drawing herein contained are illustrative merely, and that various modifications and changes may be made in the structure disclosed without departing from the spirit of the 50 invention.

Referring more particularly to the drawing, in which a preferred embodiment of the invention is 55 illustrated, the upper portion of the container is

shown generally at 10 and as there shown may be a carboy or the like.

The container 10 for which the present invention is particularly adapted has the neck portion 11 thereof provided with a shoulder or collar as 5 12 which may be inwardly tapered as shown. The invention is not, however, restricted to this specific shape of shoulder 12 as will hereinafter appear.

The container 10 is provided with a closure or 10 stopper 14 of the well known type having one or more grooves 15 diametrically disposed across the top thereof. A washer 16 of cork or other suitable material is also disposed in the well known manner between the closure 14 and the uppermost edge of the container 10. Of course, it will be understood that other forms of closure devices may be used if desired.

In accordance with the present invention a wire loop member as shown in Fig. 4 is provided, 20 preferably of an initial form as there illustrated. This loop member is preferably formed from a single piece of round wire and as illustrated in Fig. 4 includes a straight and long leg portion 17 and a closed loop 18 connected thereto. 25

The closed loop 18 preferably comprises a sharply curved portion 19 formed as a continuation of the leg 17, a generally circular portion 20 formed as a continuation of the portion 19, a continuous straight portion 21 tangentially disposed 30 with respect to the curved portion 20, a curved portion 22, an indent curved portion 23, a curved portion 24 and a short leg portion formed into a coil 25. The coil 25 is composed of a plurality of closely arranged turns of wire and surrounds the 35 portion of loop member 18 adjacent the leg 17 and the sharply curved portion 19 to provide a bearing for the portion of the loop member 18 passing through and enclosed within the coil 25.

The radius of curvature of the portion 20 and 40 the portion 24 is somewhat in excess of the radii of the neck portion 11 and of the shoulder or collar 12 of the neck of the container 10.

It is to be particularly noted that the loop member 18 is so constructed that the axis of the 45 coil 25 is co-linear with the portion 20 of the loop member 18 which extends therethrough, that the axis of the coil 25 is initially disposed horizontally and as hereinafter indicated remains disposed horizontally and in the same relative 50 position with respect to the curved portion 20.

In applying the loop member to the container, the closed loop 18 is positioned on the neck 11 of the container immediately below the collar 12 with the indent portion 23 placed on the left 55

hand side and toward the operator. The closed loop 18 is moved by the operator so that the coil 25 and the portions 20 and 24 of the closed loop 18 adjacent thereto are in contact with the neck 11 of the container below the collar 12. The straight portion or leg 17 is then bent upwardly and in the bending the adjacent portion of the closed loop 18 which comprises the end of the curved portion 20 is twisted torsionally and revolves within the bearing provided by the coil 25. This bending brings the longitudinal axis of the leg 17, as shown in Fig. 5, to a substantially vertical position and the leg 17 is thus vertically disposed above the end of the curved portion 24 where it merges into the coil 25. The leg 17 is then bent so that a portion extends upwardly along the shoulder or collar 12, as at 17a, a portion is disposed within one of the grooves 15 as at 17b of the closure 14, a portion extends downwardly along the collar 12 as at 17c. The leg 17 is thus bent into an inverted generally U-shape. The end portion of the leg 17 is inserted within the curved portion 22 or twisted therearound.

A suitable tool (not shown) may then be inserted at the portion 22 and that portion, together with the end of the leg 17 are together twisted in a manner which causes the portions of the loop member 18 adjacent the neck 11 and below the shoulder or collar 12 to be drawn into engagement with the neck portion 11 of the container 10 below the shoulder or collar 12. At the same time, the leg 17 is tightened across the top of the closure 14 and brought to a position so that the portions 17a and 17c of the leg 17 are close to the sides of the shoulder or collar 12. The final twist is shown at 26. With the conformation of loop member herein shown, the portions 17a and 17c of the leg member 17 take positions close to or against the sides of the shoulder or collar 12, while at the same time the portions 20 and 24, of the loop member 18, fit snugly against the neck 11 of the container beneath the shoulder or collar 12. The coil 25, the sharply curved portion 19, and the adjacent portions 20 and 24 of the loop member 18 extending around the neck 11, do not creep up over the shoulder or collar 12 while the loop is being fastened in position or subsequently.

It should be noted that as the straight portion or leg 17 is bent upwardly, the necessary twist of the wire to permit this bending will extend over a part of curved portion 20, the loop portion 18 of which the leg 17 is a continuation, and by reason of this torsional twist, there will be no tendency of the wire in moving to the fastening position to break or assume an undesired shape or conformation with respect to the shoulder 12 of the container in contrast to those structures wherein no torsional twist of the wire is provided.

I claim:

1. A wire loop member of a single piece of wire for fastening container closures comprising a bendable leg having a free end and being of a length sufficient to extend over the top and down the sides of the neck of the container, and a closed loop larger in size than the neck of the container, said loop being contractible by twisting portions thereof to engage the neck of the container, said loop being formed as a continuation of the bendable leg and joined to said leg by an angular bend, the other end of the wire being formed into a coil around and encircling a portion of said loop on the loop side of the bend, said coil being composed of more than a single

turn of wire and having its longitudinal axis in alignment with the loop, said coil being adapted to be horizontally disposed along and tangential to the adjacent surface of the neck of the container.

2. A wire loop member of a single piece of wire for fastening container closures comprising a bendable leg having a free end and being of a length sufficient to extend over the top and down the sides of the neck of the container, and a closed loop larger in size than the neck of the container, said loop being contractible by twisting portions thereof to engage the neck of the container, said loop being formed as a continuation of the bendable leg with an angular bend substantially at right angles therebetween, the other end of the wire being formed into a coil around and encircling a portion of said loop on the loop side of said bend, said coil being composed of more than a single turn of wire and having its longitudinal axis in alignment with the loop, said coil being adapted to be horizontally disposed along and tangential to the adjacent surface of the neck of the container, said coil serving as a journal for the coil encircled portion of the loop to permit torsional twisting thereof upon upward movement of the bendable leg.

3. A wire loop of a single piece of wire for fastening container closures comprising a bendable leg having a free end and being of a length sufficient to extend over the top and down the sides of the neck of the container, and a closed loop continuous with the bendable leg and joined therewith by an angular bend, said loop being contractible by twisting portions thereof to engage the neck of the container, the other end of the wire being formed into a coil around a portion of the loop near its juncture with the bendable leg and on the loop side of the bend, said coil having its longitudinal axis in alignment with the loop, said bendable leg having the free end for engagement with a portion of the loop remote from the coil, and a deflected portion formed in said loop to indicate the initial positioning of said loop.

4. The combination with a container having a neck with a shoulder at the upper extremity, and a closure member for closing the mouth of the container, of a fastening member for holding said closure member in position, said fastening member including a portion encompassing the neck below the shoulder of said container, the neck encompassing portion having a part thereof twisted for holding said portion in engagement with the container neck, said neck engaging portion having one of its ends formed into a coil consisting of more than one turn, said coil being horizontally disposed along said neck below said shoulder, said coil having a central opening therethrough through which another portion of the neck encompassing portion extends, the portion through said coil being torsionally twisted therein and beyond the end of said coil extending upwardly at an angle to the axis of said coil, the upwardly extending portion passing over the top and in engagement with the closure member and having its terminal end in engagement with the twisted part of the neck encompassing portion.

5. The combination with a container having a neck with a collar at the upper extremity, and a closure member for closing the mouth of the container, of a member for holding said closure member in position, said fastening member in-

cluding a portion encompassing the neck below the collar of said container, the neck encompassing portion having a part thereof twisted for holding said portion in engagement with the container neck, said neck engaging portion at a location on the neck opposite said twisted part having one of its ends formed into a coil consisting of more than one turn, said coil being tangentially disposed along said neck below said collar, 5
10 said coil having a central opening therethrough through which another portion of the neck encompassing portion extends, the portion through said coil being torsionally twisted therein and beyond the end of said coil extending upwardly substantially at right angles to the axis of said coil, the upwardly extending portion being extended to provide an inverted U-shaped portion in engagement with the closure member and extending across the top thereof, said U-shaped portion having a part remote from said coil in engagement with the twisted part of the neck encompassing portion.

6. The combination with a container having a neck with an enlarged collar at the upper extremity, and a closure member for closing the

15 mouth of the container, of a fastening member for holding said closure member in position, said fastening member including a portion encompassing the neck below the collar of said container, the neck encompassing portion having a part thereof twisted for holding said portion in engagement with the container neck, said neck engaging portion at a location on the neck opposite said twisted part having one of its ends formed into a coil consisting of more than one turn, said coil being tangentially and horizontally disposed along and in engagement with said neck below said collar, said coil having a central opening therethrough through which another portion of the neck encompassing portion extends, 10 the portion through said coil being torsionally twisted therein and beyond the end of said coil extending upwardly substantially at right angles to the axis of said coil, the upwardly extending portion being extended to provide an inverted U-shaped portion in engagement with the closure member, said U-shaped portion having its terminal end intertwined with the twisted part of the neck encompassing portion.
